ABSTRACT: A louver construction to be used as a false ceiling and for other purposes, which generally comprises parallel support runners and rows of light-diffusing panels or baffles of incomplete latticework construction. The runners are the same thickness as the ribs of the panels and intersect the ribs of the panel which are perpendicular to the endmost ribs at a distance inside the endmost ribs. Thus, when the panels are mounted adjacent one another on the support runners, the incomplete latticework of the panels is completed and the effect is of an uninterrupted latticework construction.

LOUVER CONSTRUCTION

BACKGROUND OF THE INVENTION

1. Field of the Invention

The present invention relates generally to a louver construction for ceilings or other purposes, and more particularly to a simplified louver construction comprising parallel support runners and rows of light-diffusing panels adapted to be supported on adjacent pairs of the runners for quick and easy installation and subsequent removal.

While high levels of illumination have been achieved with high-intensity light sources, such as fluorescent lamps, it has been necessary to control the brightness and glare to provide visual comfort. This has been accomplished with light diffusing means, such as false ceilings provided with louver constructions formed from a plurality of light diffusing panels, baffles or grids. Each panel may be a cellular or eggcrate construction comprising a latticework arrangement of intersecting ribs which may be open through the top and bottom. Light is permitted to pass directly downwardly through the cells formed by the intersection of ribs, however, when viewed from an angle, the ribs of the panels block direct light so that much of the light observed is deflected or diffused light. The light-diffusing panels may, for example, be square or rectangular units about 2 feet across and may be supported in edge-to-edge relation to form a louver construction false ceiling that extends across the entire room from wall to wall, or across only a portion of the ceiling area. It is desirable that some, if not all, of the panels be individually removable with facility to afford access to the area above the false ceiling and particularly to the light fixtures. It is also desirable that the meeting or joining lines between adjacent panels be as inconspicuous or unnoticeable as possible to create the illusion of an unbroken latticework arrangement of intersecting ribs across the entire ceiling area.

In addition to these requirements, it is most important to be able to install these panels quickly and easily, without special tools or skills, and with a minimum of support structure. It is also desirable, of course, that the panels be relatively simple and economical to manufacture and assemble.

2. Description of the Prior Art

Prior light-diffusing panel louver ceiling constructions have not been fully satisfactory. Some prior constructions, while being simple, have been difficult, time consuming, and costly to properly install and/or have not permitted rapid and easy removal of individual parts. Further, light leaks between adjacent panels have often been present, creating distractions and impairing the continuous uniform appearance of the ceiling. Other constructions have been excessively complicated and costly to manufacture and install and/or have not afforded ready removal of individual parts. In particular, support structures for the panels have been complicated, difficult to install and to connect to the panels, and required particular tools and/or skills for the installation. Some of the current light-diffusing panels employ the "trackless" construction which means that there are no apparent support runners. This is as opposed to constructions using inverted T-shaped suspension members or the like. The current "trackless" louver suspension systems have a relatively straight line of abutment between adjacent panels along the suspension member and thus any slight gaps between the abutting panels show up as a line of light and thus uniform light diffusion is interrupted.

The present louver suspension systems place the support means or runners outside the endmost ribs of the panels in engagement with projecting portions of the ribs which are at right angles to said endmost ribs and therefore the dimensions of the panel must not exceed given amounts if sagging of the panel is to be avoided. In addition, since these projecting portions of the ribs are subject to damage and bending during manufacturing, packaging, handling, installing, and maintaining the suspension points or the points at which the ribs interengage with the support means may not hold their relationship to one another thereby making it difficult to insert the

projecting ends of the ribs into the slots in the support runners. Additionally, the angle of light reflectance from bent projections causes the projections to take on either a lighter or darker shadowing than the balance of the louver blades, seriously impairing the overall appearance of the ceiling.

SUMMARY OF THE INVENTION

The present invention contemplates a light-diffusing panel louver construction which is simple and economical to manufacture and install, which provides quick and easy removal of individual panels and which creates the illusion of a continuous louver ceiling because there is uniform light diffusion over the whole of its surface.

In a louver construction in accordance with the invention, there is provided elongate, spaced, parallel support runners adapted to be supported below a ceiling carrying a light source; light-diffusing panels adapted to be mounted on said support runners, each panel comprising an incomplete latticework arrangement of intersecting ribs, said runners being of the same thickness as said ribs, two opposed ends of said panel having endmost ribs, such engagement occurring at a distance inside said endmost ribs which is equal to or is a multiple of the distance between adjacent ribs, said runners when engaged with the panel, completing the latticework arrangement and extending beyond edges of the panel to complete the incomplete latticework arrangements in at least two adjacent panels, means for suspending said runners being located on the runners at locations which correspond to an edge of a panel to enable assembly of a plurality of such panels and runners in coplanar relationship.

Installation of current panels is very often difficult because some of the projecting ribs adapted to intersect with and interengage the support runners become bent or twisted, thus preventing proper alignment. In the panel according to the present invention, the suspension points or the points at which the ribs are to interengage the support runners are inside the endmost ribs and therefore are not subject to this sort of damage. The relatively fixed position of the suspension points also facilitates installation.

This invention possesses many other advantages, and has other objects which may be made more clearly apparent from a consideration of a form in which it may be embodied, but it is to be understood that the detailed description of this form is not to be taken in a limiting sense. This form is shown in the accompanying drawings. It will now be described in detail, for the purpose of illustrating the general principles of the invention.

BRIEF DESCRIPTION OF THE DRAWINGS

FIG. 1 is a plan view of a panel made in accordance with the invention; and

FIG. 2 is an exploded perspective view of adjacent panels and a support runner made in accordance with the invention.

DESCRIPTION OF THE PREFERRED EMBODIMENTS

The louver construction includes, as shown in FIGS. 1 and 2, elongate, spaced, parallel support runners 26. Rows (not shown) of panels 28 are supported on pairs of support runners 26. There are no connections between the panel 28 and the adjacent panels in a row, shown in phantom in FIG. 1 at 20A, and there is no direct interconnection between panel 28 and the panels in the adjacent rows, shown in phantom in FIG. 1 at 20B. Each panel is comprised of an incomplete latticework arrangement of intersecting ribs 30 and 32 which interengage the support runners 26 whereby the panel is supported.

The ends of the ribs 30, 32 terminated at different points 70 lengthwise and crosswise of a panel to mate with ribs of adjacent panels and with the support runners to provide continuity in the latticework arrangement between adjacent baffles and to avoid the straight line light leaks between adjacent panels as described above. The support runners 26 are the same thickness as the ribs and extend beyond the edges of the

panel to complete the incomplete latticework arrangements in at least two adjacent panels thereby creating the illusion of a continuous latticework across the entire ceiling.

The embodiment shown and described is a preferred form of the invention and it is to be understood that the panels 28 could also be rectangular in shape without departing from the invention.

In the embodiment shown, a tongue-and-groove arrangement is provided wherein each support runner passes through the tongue 40 and across the groove 42 of adjacent panels 28. In this arrangement the length of the runners 26 exceeds the width of the panel 28 and thus not only supports adjacent panels 20A indicated by the tongue-and-groove configuration but also abutting panels 20B. Each runner thus completes the latticework arrangement in its own plus three other panels.

Each of the support runners has spaced vertical slots 34 (FIG. 2) extending downwardly from its upper edge to about its midpoint. Each runner 26 also includes apertures 36 adjacent to its upper edge to receive the lower ends of a suspension means, such as wires 38 (FIG. 2) or the like, supporting the runners, the upper ends of the suspension means being secured to eyes (not shown) fixed to the permanent ceiling. To enable assembly of a plurality of panels and runners in coplanar relationship, each of the apertures 36 must be located on the runners at a location which corresponds to an edge of a panel. The vertical slots 34 in the runners receive ribs 30 of the panels, and thereby support the panels on the runners.

A louver construction will normally be made up of a number of light-diffusing panels 28.

The ribs 30, 32 are slotted in a known manner so as to interengage with one another to form a latticework arrangement of intersecting ribs. Of course, if it is desirable from an aesthetic or design point of view, the lower edges of the ribs may be provided with projections and recesses so as to give the louver construction a textured appearance when seen from below. Indeed, the latticework arrangement shown in the attached drawings may be altered and is only shown here in a common form. It should be noted that the interlock serves to restrict both transverse and longitudinal relative movement between the ribs 30, 32. The ribs 30, 32 are constructed of metal and the slots are made very slightly shallower than one-half the height of the ribs 30, 32 which they respectively receive, so that the ribs are interconnected by a press fit which serves to displace metal and provide a relatively permanent connection between the ribs. Alternatively, if desired, the strips may be interconnected permanently as, for example, by means of welding.

The runners 26 engage the ribs 30 with intersect the endmost of the ribs 32. The engagement may occur at a distance inside the endmost of the ribs 32 which is equal to or is a multiple of the distance between adjacent ribs. If comparatively long panels are to be used, then it is recommended that the runners 26 be a number of cell widths inside the endmost of the ribs 32 to reduce the span between them and avoid sagging

of the intermediate portions of the panels.

The installed louver ceiling construction thus conveys the illusion of continuity in both directions by virtue of the continuous, regularly spaced series of longitudinally extending ribs or strips 30 and support runners 26, and the continuous regularly spaced series of transversely extending ribs or strips 32.

Any one of the panels 28 may be readily removed by lifting upwardly from the support runners 26 and tilting it to permit its lowering through the space it occupied between adjacent support runners 26 and adjacent panels.

Thus a louver construction has been provided which is particularly simple to install without the necessity of special tools or skills, and in which any one of the panels may be quickly and easily removed when desired. At the same time, an illusion of continuity is provided of the entire area of the louver ceiling.

Unlike other current "trackless" louver suspension systems, the system described above could successfully employ the use of light-diffusing plastic panels on top of the panels 28 by trimming the plastic panels to the tongue-and-groove shape of the panels 28 and by restricting the rib projections to one-half cell. This would change the louver from an open ended cellular construction to a closed cellular construction.

I claim:

1. In a louver construction, elongate, spaced, parallel support runners adapted to be supported below a ceiling; light-diffusing panels removably mounted on said support runners; each panel comprising an incomplete latticework arrangement of intersecting ribs, said runners being of the same thickness as said ribs, two opposed ends of said panel being endmost ribs, said runners engaging the ribs which intersect the endmost ribs, such engagement occurring at a distance inside said endmost ribs which is equal to or is a multiple of a distance between adjacent ribs, said runners when engaged with the panel completing the latticework arrangement and extending beyond edges of the panel to complete the incomplete latticework arrangements in at least two adjacent panels, for means for suspending said runners being located on the runners at locations which correspond to an edge of a panel to enable assembly of a plurality of such panels and runners in coplanar relationship.

2. A louver construction according to claim 1, wherein said panel is formed at one of said two opposed ends with a projection of said latticework and at the other of said ends with a recess in said latticework whereby a tongue and groove arrangement is formed.

3. A louver construction according to claim 2, wherein said runner passes through said projection of one panel and across said recess of an adjacent panel.

4. A louver construction according to claim 1, wherein each of said panels has certain of its ribs freely extending beyond the edges thereof and adapted to abut and align with freely extending ribs of adjacent panels thereby to create the illusion of a continuous latticework arrangement of intersecting ribs between adjacent panels.
